UNITED STATES PATENT OFFICE.

OMER M. GLUNT, OF RUTHERFORD, NEW JERSEY, ASSIGNOR TO WESTERN ELECTRIC COMPANY, OF NEW YORK, N. Y., A CORPORATION OF ILLINOIS.

CONNECTING PLUG.

1,097,220.

Specified December 1, 1914. Patented May 18, 1914.

Application filed April 1, 1912. Serial No. 762,684.

To all whom it may concern:

Be it known that I, OMER MANN GLUNT, a citizen of the United States, residing at Rutherford, in the county of Bergen and State of New Jersey, have invented a certain new and useful Improvement in Connecting Plugs, of which the following is a full, clear, concise, and exact description:

This invention relates to connecting plugs and has for its object the production of a connecting plug of few and simple parts so arranged as to be readily accessible.

The features of this invention are the improved means for providing for the ready assembly of the parts of the plug, the improved means for the ready connecting of the conductors of the associated need to the contact making members of the plug, and other details of structure and combination of parts as will hereinafter more clearly appear.

This invention is illustrated in the accompanying drawing in which the same reference characters are used throughout to designate the same parts, and in which:

Figure 1 is a side elevation with the views in section, of a plug embodying this invention; Fig. 2 is a sectional view of the plug on line 2-2 of Fig. 1, and Fig. 3 is a detail perspective view of the various parts of the plug before assembly.

The plug comprises, a main body portion having a web portion 1 connecting end portions 2 and 3. The web portion 1 is provided with flat surface 6. Formed upon the end portion 3 is a sleeve contact 7 which is indented to receive an insulating sleeve 8, a conducting sleeve 9, an insulating sleeve 10, and a conductive and connecting bolt 15 mounted one within the other in the sequence named. The said bolt 15 has a threaded portion 11 on its outer end and a threaded portion 12 on its inner end. The insulating sleeve 8 has formed on the outer end thereof a flanged portion 16. Carried on the outer end of the conducting sleeve 9 is a ring contact 17, insulated from the sleeve contact 7 by the flanged portion 16 of the insulating sleeve 8. A top contact 18 is mounted on the outer end of the conducting and connecting bolt 15 and is insulated from the ring contact 17 by an insulating bushing 19.

An insulating bushing 20, having a threaded portion 26 adapted to register with the

surface 6 of the web portion 1 of the body, is mounted upon the inner end of the insulating sleeve 8. A terminal 27, having an extension 29 formed thereon, which extension is drilled and tapped to receive one of the screws 24, has a flat edge 28 adapted to register with the upper surface of the flanged portion 23 of the insulating bushing 20.

This terminal 27 is mounted upon the inner end of the conducting sleeve 9 and is insulated from the sleeve 20 and the body 65 of the plug by the insulating bushing 20. An insulating bushing 20, having a cutaway portion 21 with which the extension 29 of the terminal 27 engage, is mounted upon the flat surface 6 of the web portion 1 of the body. A terminal 27, having formed thereon an extension 24 which is drilled and tapped to receive one of the screws 24, and having a flat edge 28 adapted to register with the upper surface of the flanged portion 23 of the insulating bushing 20, is also mounted upon the conducting and connecting bolt 15 near its inner end. The terminal 27 is insulated from the terminal 27 and the body by the insulating bushing 20.

A nut 40 engages the threaded portion 12 of the inner end of the conducting and connecting bolt 15 to maintain the insulating bushing 20, ring contact 17, insulating sleeves 8 and 10, conducting sleeve 9, insulating bushings 20 and 30, and terminals 27 and 28 in position. The flat surface 6 of the web portion 1 is drilled and tapped at 4 to receive one of the screws 24, and forms one terminal of the plug. The covering sleeve 13 is closed the body portion of the plug and is held in place by the engagement of screw 14 with end portion 2. The terminals 27 and 28 are prevented from rotating by the engagement of their respective flat edges 28 and 32, the dangers 26 and 32 of the insulating bushings 20 and 30 and the flat surface 6 of the web portion 1. The terminals 27 and 28 are so mounted that their respective extensions 29 and 34 are on opposite sides of the bolt 15, so that they have a wide angle of separation, as shown in Fig. 1. The outer portion of the sleeve 13 is closed with a stop 14 at each end, and the sleeve is closed 100 in the flat portion 1.

of a screw driver when connecting the conductors of the associated cord to the terminals.

On account of the simplicity of the few parts and the convenient arrangement thereof, the assembly of plug can be accomplished in a minimum amount of time and at a minimum cost.

It will be readily apparent that, with the plug assembled as above described, the conductors of the associated cord may be readily connected to or disconnected from the terminals by removing the screw 14 and slipping back the covering sleeve 13; and with the covering sleeve 13 removed, any of the parts mounted upon the bolt 15 may be readily replaced by the removal of the nut 40.

While a plug having three contact members has been described, it is readily apparent that the number may be decreased or increased without departing from the spirit of this invention, and therefore the invention is not limited to the number of contact members as shown and described.

What I claim is:

1. A connecting plug comprising a body having a web portion formed thereon, a plurality of contact members carried by said body, a terminal having a flat edge and se-

cured to one of said contact members, and an insulating member having a flange formed thereon, separating said terminal and said body, said flange engaging said web portion and said flat edge to prevent the rotation of said terminal.

2. A connecting plug comprising a body, a tip contact, a ring contact, a bolt for securing said tip and ring contacts to said body, terminals for said tip and ring contacts mounted upon said bolt, and angular extensions on said terminals located upon opposite sides of said bolt.

3. A connecting plug comprising a body, a tip contact, a ring contact, a bolt for securing said tip and ring contacts to said body, terminals for said tip and ring contacts mounted upon said bolt, angular extensions on said terminals located upon opposite sides of said bolt, and insulating members separating said terminals from each other and from said body, and maintaining the angular position of said terminals.

In witness whereof, I hereunto subscribe my name this 17th day of April A. D., 1913.

OMER M. GLUNT.
